CLAIM

The ornamental design for a hair dryer, as shown and described.

DESCRIPTION

FIG. 1 is a perspective view of a hair dryer showing our new design;

FIG. 2 is a top plan view thereof;

FIG. 3 is a bottom plan view thereof;

FIG. 4 is a left side elevation view thereof;

FIG. b 5 is a right side elevation view thereof;

FIG. 6 is a front elevation view thereof; and,

FIG. 7 is a rear elevation view thereof.

The cord portion of the design is shown partially broken away in FIGS. 3-5 to indicate indeterminate length; and omitted in FIGS. 1, 6 and 7 for ease of illustration.
